US00D654524S

(12) **United States Design Patent**
Iversen et al.

(10) **Patent No.:** US D654,524 S
(45) **Date of Patent:** ** Feb. 21, 2012

(54) **LINEAR ACTUATOR**

(75) Inventors: **Torben Iversen**, Nordborg (DK); **Rene Sørensen**, Gråsten (DK); **Martin K. Knudsen**, Sydals (DK)

(73) Assignee: **Linak A/S**, Nordborg (DK)

(**) Term: **14 Years**

(21) Appl. No.: **29/371,686**

(22) Filed: **Jul. 8, 2011**

(30) **Foreign Application Priority Data**

Jan. 26, 2011 (DK) 2011 00011

(51) **LOC (9) Cl.** **15-99**

(52) **U.S. Cl.** **D15/199**

(57) **CLAIM**

The ornamental design for a linear actuator, as shown and described.

DESCRIPTION

FIG. 1 is a perspective front view of a linear actuator showing our new and ornamental design,

FIG. 2 is a perspective rear view thereof,

FIG. 3 is a right side elevational view thereof,

FIG. 4 is a left side elevational view thereof,

FIG. 5 is a bottom plan view thereof,

FIG. 6 is an elevational rear view thereof,

FIG. 7 is an elevational front view thereof; and,

FIG. 8 is a top plan view thereof.

The broken lines in the drawings depict unclaimed environmental subject matter.
